(57) **CLAIM**

The ornamental design for a utility knife, as shown and described.

DESCRIPTION

FIG. 1 is a first perspective view of a utility knife showing my new design;

FIG. 2 is a second perspective view thereof; aa

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front view thereof, wherein the actuator is in the compressed position; and,

FIG. 10 is a rear perspective view thereof, wherein the actuator is in the compressed position.

The broken lines shown in the drawings depict portions of the utility knife that form no part of the claimed design.

1 Claim, 10 Drawing Sheets
